Tomson and Decker

UNITED STATES PATENT OFFICE.

JAMES H. GRAVELL, OF ELMINS PARK, PENNSYLVANIA.

LEAKPROOF LIQUID CONTAINER.

Application filed April 8, 1920. Serial No. 372,119.

To all whom it may concern:

Be it known that I, JAMES H. GRAVELL, a citizen of the United States, and a resident of Elkins Park, in the county of Montgomery and State of Pennsylvania, have invented certain new and useful Improvements in Leakproof Liquid Containers, of which the following is a specification.

My invention relates to containers and has for its object the production of a novel container which shall be simple in construction, easily manufactured, durable and leak-proof, the invention further having for its object the charging of a container with the material to be shipped or stored by an improved and novel method or process.

The invention is peculiarly applicable to containers adapted to hold corrosive liquids such as acids but it may be employed with equal advantage in the case of neutral liquids such as wines, alcohol or even water. The invention, furthermore, is not limited to the use of liquids, but solids, such as sand, flour and dry powdered materials, which have the quality of inflating a suitable envelope or bag when poured therein may also be used in connection with the invention.

Briefly stated the invention consists in the providing of a suitable outer rigid supporting casing preferably having a restricted opening therein, arranging the body but not the end or mouth of an inflatable bag or envelope, which is of liquid-tight material and preferably of rubber or other expandable, elastic material, the mouth or end being, if desired, supported in the opening in the supporting casing, filling the inflatable bag through its end or mouth with the material to be stored or shipped whereby the bag will be inflated or extended and will conform substantially in shape to and be supported by the casing and closing and sealing the neck of the inflatable bag and the opening in the casing.

The invention consists also in details of construction and combinations specified more particularly in the claims.

In the accompanying drawing illustrating a practical embodiment of the invention:

Fig. 1 is a perspective view of my improved inflatable bag or envelope shown in collapsed and folded or rolled-up position.

Fig. 2 is a perspective view of the sup-

porting casing with the body of the inflatable bag partially inserted therein.

Fig. 3 is a perspective view of the container when filled and ready for shipment or use.

Fig. 4 is a sectional view of a modified form of casing showing the inflatable bag or envelope therein partially filled with material.

Fig. 5 is a view similar to Fig. 4 but showing the inflatable bag or envelope filled and the container ready for storage or shipment.

My improved container comprises two parts to wit: an outer rigid supporting casing and an inner inflatable bag or envelope. Said supporting casing is shown as a glass bottle in Figs. 2 and 3, the body of which is indicated at 1 and its neck at 2. The neck or mouth 2 may be provided with the usual flange or bead 3. 4 indicates the body of the inflatable bag or envelope which is provided with a flange 5 adjacent its end or mouth. Said bag or envelope is preferably made of thin rubber or other similar material which is inflatable or expansible and which is at the same time inert to the chemical action of an acid, and it simulates to a great extent the ordinary toy balloon in which the mouth or body are connected in an air-tight or liquid-tight manner.

To fill the container with the material it is desired to store or ship the body of the inflatable bag or envelope is rolled up or folded and is slipped through the neck of the casing as shown in Fig. 2 and into the body thereof. A glass tube 6 or other air-expelling device may then be inserted intermediate the neck of the casing and the bag or envelope filled through its mouth with the liquid acid or other material. The filling of the bag causes it to inflate or expand outwardly against the walls of the casing which support the same, in an obvious manner, the inflation or expansion of said bag or envelope forcing the air in the casing outwardly through the tube 6 and preventing the formation of air pockets in the casing. When the bag or envelope is filled to the desired extent the tube 6 is withdrawn, the flange 5 on the mouth of the bag or lining is turned over the flange 3 on the neck or mouth of the casing and a suitable solid stopper 7 preferably of rubber or other non-corrodible material

is inserted in the mouth of the casing in engagement with the mouth of the bag, the mouth containing said stopper being held against expansion by its engagement with the inner wall of the neck or opening when the stopper is inserted. The insertion of said stopper thus seals and encases in rubber the liquid within the container and the liquid is strongly protected and is not permitted to contact with the casing 1 or any portion thereof.

In the forms of the invention illustrated in Figs. 4 and 5, I show the invention applied to an ordinary barrel or box 8 having an opening or bung-hole 9. The bag or envelope which is made to conform more or less to the shape of the barrel or box is inserted in the bung-hole as in the previous case and the bag then filled to the desired extent. The neck of the bag or envelope immediately below the flange 5 may be then securely tied or otherwise sealed and the neck pushed down within the bung-hole 9 as shown in Fig. 5 and an ordinary bung 10 driven into the bung-hole. In this case I may provide the casing with perforations 11 which have the same function as the tube 6, to wit: the permitting of air to escape from the casing and which accordingly permit the operator to dispense with the use of said tube. In drawing liquid or other material therein from the container, it is handled in exactly the same way as it would be had it not contained the bag. A hole is drilled at the desired place which operation punctures the rubber bag or envelope. A spigot is then inserted in the hole in the regular way and the bung is removed. The rubber bag may or may not be punctured at the bung in order to let air in to replace the liquid flowing out of the hole, as the rubber bag readily collapses.

While I have described the bag or envelope being made of rubber it is obvious that it may be made of other inflatable liquid tight materials such as oiled silk or oil-cloth if so desired. The casing, moreover, may be constructed of any rigid material as glass, wood or metal.

50 What I claim as my invention is:—

1. A container comprising a rigid casing having an opening, a lining of expandable liquid-tight material having a neck or mouth adapted to be supported in said opening and said lining being inflated by insertion of the contents therein and thereby conformed to the inner shape of the casing and supported thereby.

2. A container comprising a rigid casing having a restricted opening, a lining therefor composed of elastic, expandable material like rubber arranged in said casing and having a mouth in the restricted opening, said lining being adapted to be inflated and expanded by insertion of the contents and

thereby conform to and be supported by the inner shape of the casing and means for sealing said lining.

3. A container comprising a rigid outer casing having a restricted opening, an inflatable soft rubber lining having a rubber mouth in said restricted opening, said lining therefore being adapted after insertion in the casing to be expanded by inserting material therein whereby said bag will conform to the inner shape of the casing and means for sealing said lining by a stopper inserted in the rubber mouth while arranged in the restricted opening.

4. A container comprising a rigid outer casing having a restricted opening, a thin rubber bag having a filler opening and adapted to be inserted in the casing in collapsed condition through the restricted opening, said bag being adapted to be inflated and expanded by the contents thereof and thereby conform to the inner shape of the casing and means for sealing the filler opening within the casing.

5. A container for liquids consisting as 90 to its outer walls of rigid material and having an inner wall or lining consisting of flexible, elastic material like rubber having a rubber mouth, said lining being held in and supported by the rigid casing and conforming thereto by the contents of the container introduced into said lining through said mouth.

6. A container for liquids comprising a rigid casing and an acid-proof lining consisting of an expansible, elastic material held expanded into contact with and conforming to the inside of the casing by the liquid contents.

7. A barrel having a lining consisting of 105 an acid-proof, liquid-tight container having a mouth adapted to be arranged in the bung-hole of the barrel for filling, said lining being held expanded against and supported by the inside of the barrel by the action of the 110 liquid introduced therein through said mouth.

8. A liquid container comprising an outer casing of rigid material and a lining of elastic, expandable material like rubber having 115 a restricted filling mouth arranged in a restricted mouth of the casing, said lining being held, conformed to and supported by the inner wall of the casing by the liquid contents and being provided with a stopper 120 engaging in the mouth of the lining where it projects through the restricted mouth of the casing.

Signed at New York, in the county of New York and State of New York, this 7th 125 day of April, A. D. 1920.

JAMES H. GRAVELL.
